UNITED STATES PATENT OFFICE

103,499

DESIGN FOR A VACUUM CLEANER

Harold W. Hofmaster, Great Bend, Kans.

Application July 22, 1936, Serial No. 63,986

Term of patent 3½ years

To all whom it may concern:

Be it known that I, Harold W. Hofmaster, a citizen of the United States, residing at Great Bend, in the county of Barton and State of Kansas, have invented a new, original, and ornamental Design for a Vacuum Cleaner, of which the following is a specification, reference being had to the accompanying drawing, forming part thereof.

Figure 1 is a view in side elevation of a vacuum cleaner, showing my new design.

Figure 2 is a view in front elevation thereof.

I claim:—

The ornamental design for a Vacuum cleaner, as shown.

HAROLD W. HOFMASTER.
